CLOSURE WITH VALVE FOR BOTTLES OR THE LIKE

Application filed August 1, 1931, Serial No. 554,554, and in Mexico June 12, 1931.

This invention refers to a closure for bottles or the like, and its object is to provide a construction particularly applicable to the crown type of bottle cap, and which will allow the operations of producing vacuum or pressure in the bottle to be performed after the cap or closure has been applied.

In the accompanying drawing are shown four pieces which constitute the closure, respectively in Figs. 1-4, while Fig. 5 represents a cross section of the complete closure showing the relative position of the four pieces.

In said drawing:

- 15 Fig. 1 represents the exterior metallic cap.
- Fig. 2 represents the valve member;
- Fig. 3 represents the valve chamber.
- Fig. 4 represents the washer.
- 20 Fig. 5 represents the complete closure in vertical cross section.

With reference to the figures of said drawing, 1 is the exterior metallic cap, 2 the cylindrical valve chamber which is provided, in its open end with an annular flange 3 which may be adjusted without pressure in the inside of the metallic cap 1. Said valve chamber is provided with a perforation in its closed end, said perforation communicating with the interior of the bottle or the like. 4 is the washer which may be made of cork, rubber or any other convenient material, and which is of a slightly greater diameter than that of the metallic cap so that it will enter into said metallic cap with pressure. Before it is inserted in said cap, it is placed on the flange of the valve chamber, wherefore it will serve as a support for same within the metallic cap.

Before introducing the valve chamber with the washer in the metallic cap, the valve 5 is placed in the interior of the valve chamber in order to seal the hole 6 of the same or the hole 7 of the metallic cap 1.

The metallic cap 1 is provided with a hole 7 made from the outside inwardly with the object of producing a burr 8 on the inside, which will prevent the valve 5 closing completely the hole 7 during the operation of forming vacuum in the bottle or the like, thus allowing the air or gas to be extracted.

When the closure is used on bottles or the like in which it is desired to form pressure, then the burr is made on the hole 6 of the valve chamber instead of on the hole 7 of the metallic cap, with the object of preventing the valve closing completely said hole 6 during the operation of producing pressure in the bottle or the like by introducing air or gas. In this case a burr is also provided on the outer surface of the cap around the hole 7, which will make it possible to seal said opening with solder.

Once the bottle or the like is filled, the cap or closure is placed, and according to the class of valve action selected and the corresponding placing of the burrs, the valve member 5 will close or seal either the hole of the valve chamber or that of the metallic cap by the corresponding operation of producing vacuum or pressure in the bottle, making it impossible for the air or gas to escape from or enter into the bottle, respectively.

The closure according to the present invention can be applied with the machinery actually in use for crown capping, as the whole aggregate is confined within the limits of the ordinary standard cap of the "crown" type.

Having thus described the invention, what I claim is:

1. A valved closure for bottles and the like which will permit the passage of gas through the closure in one direction after it has been applied, comprising a cap, a tubular element having one end open and the other end closed, an annular flange surrounding the open end, said tubular element being positioned in the cap with the annular flange lying against the inner face of the top of the cap and adapted to lie between this face and the rim of the bottle when the cap is applied on the bottle, the closed end of the tubular element and the central portion of the cap being provided with apertures, and a valve body loosely positioned in the tubular element adapted to close one of the apertures.

2. A valved closure for bottles and the like which will permit the passage of gas

- through the closure in one direction after it has been applied, comprising a cap, a tubular element having one end open and the other end closed, an annular flange surrounding the open end, said tubular element being positioned in the cap with the annular flange lying against the inner face of the top of the cap and adapted to lie between this face and the rim of the bottle when the cap is applied on the bottle, the closed end of the tubular element and the central portion of the cap being provided with apertures, a valve body loosely positioned in the tubular element adapted to close on the apertures, and means associated with the aperture in the cap for preventing closing of this aperture by the valve body to permit withdrawal of gas from the bottle.
3. A valved closure for bottles and the like which will permit the passage of gas through the closure in one direction after it has been applied, comprising a cap, a tubular element having one end open and the other end closed, an annular flange surrounding the open end, said tubular element being positioned in the cap with the annular flange lying against the inner face of the top of the cap and adapted to lie between this face and the rim of the bottle when the cap is applied on the bottle, the closed end of the tubular element and the central portion of the cap being provided with apertures, a valve body loosely positioned in the tubular element adapted to close one of the apertures, and means associated with the aperture in the closed end of the tube for preventing closing of this aperture by the valve body to permit the introduction of gas into the bottle.
4. A valved closure for bottles and the like which will permit the passage of gas through the closure in one direction after it has been applied, comprising a cap, a tubular element having one end open and the other end closed, an annular flange surrounding the open end, said tubular element being positioned in the cap with the annular flange lying against the inner face of the top of the cap and adapted to lie between this face and the rim of the bottle when the cap is applied on the bottle, the closed end of the tubular element and the central portion of the cap being provided with apertures, and means associated with the aperture in the cap for preventing closing of this aperture by the valve body to permit withdrawal of gas from the bottle.

tures, a valve body loosely positioned in the tubular element adapted to close one of the apertures, and means associated with one of said apertures to prevent closing thereof to permit the flow of gas through this opening.

5. A valve closure for bottles and the like which will permit the withdrawal of gas from the bottle after the closure has been applied, comprising a cap, a tubular element having one end open and the other end closed, an annular flange surrounding the open end, said tubular element being positioned in the cap with the annular flange lying against the inner face of the top of the cap, a resilient gasket positioned in the cap adapted to bear against the annular flange to retain the tubular element within the cap, the closed end of the tubular element being provided with an aperture and the central portion of the cap being provided with an aperture, the latter aperture having a burr surrounding the same on the interior face of the top of the cap, and a valve body loosely positioned in the tubular element adapted to close the aperture in the closed end of the tube.

6. A valve closure for bottles and the like which will permit the introduction of gas into the bottle under pressure after the closure has been applied, comprising a cap, a tubular element having one end open and the other end closed, an annular flange surrounding the open end, said tubular element being positioned in the cap with the annular flange lying against the inner face of the top of the cap, a resilient gasket positioned in said cap and adapted to maintain the annular flange against the inner face of the top of the cap, the closed end of the tubular element and the central portion of the cap being provided with apertures, a valve body loosely positioned in the tubular element adapted to close the aperture in the top of the cap, the aperture in the closed end of the tubular element being surrounded by a burr which cooperates with the valve body to prevent closing of this aperture, and the aperture in the top of the cap being provided with an external burr for the reception of a sealing agent.
